UNITED STATES PATENT OFFICE.

CHARLES J. NASH, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-GEAR.

1,036,511.

Specification of Letters Patent. Patented Aug. 20, 1912.

Application filed May 15, 1912. Serial No. 697,407.

To all whom it may concern:

Be it known that I, CHARLES J. NASH, a citizen of the United States, and resident of Chicago, county of Cook, and State of Illinois, have invented certain new and useful Improvements in Draft-Gears, of which the following is a specification, and which are illustrated in the accompanying drawings, forming a part thereof.

10 The invention relates to an improvement in the draft gear which forms the subject of my pending application for Letters Patent Serial No. 664,461, its object being to provide an improved form of spacing and 15 retaining plate used in connection with twin spring gears.

As pointed out in the application referred to, the retaining plate is necessarily wrought to its service form in part after the gear is 20 assembled, by bending some of its leaves. The assembling is usually done in yards where it is not convenient to heat the parts to be bent, and the purpose of the present invention is to provide a form of plate which, 25 while having ample body to properly space the springs, is provided with leaves which, because of their form and relative disposition, may be readily bent as required, without being heated.

30 The invention is illustrated in the accompanying drawings, in which—

Figure 1 is a perspective of the spacing and retaining plate, its original form being shown in solid lines, and its service form 35 in dotted lines; Fig. 2 is a longitudinal vertical section of a draft gear showing the spacing and retaining plate in service, some parts of the car construction being shown in detail; Fig. 3 is a transverse section on 40 the line 3—3 of Fig. 2.

There are shown in the drawings the central sills, 10, 11, of a car, each being provided with a suitable draft-arm, 12, 13; the yoke, 14; a coupler-bar, 15, and forward 45 and rearward followers, 16, 17, the latter being integral with the yoke. There are also shown two sets, 18, 19, of springs, interposed between the follower-plates and arranged side by side, or, as known in the 50 art, as twins. These two sets of springs are arranged in vertical alinement, engaging, re-

spectively, the bottom and top side members of the yoke, which are shown as concave, for the purpose of preventing material lateral movement of the springs.

55

The springs are spaced apart by means of the spacing and retaining plate shown in detail in Fig. 1. This plate is preferably a malleable casting, having a central body portion, 20, of sufficient thickness to properly 60 space the springs and provide adequate strength, and leaves, 21, 22, 23, 24, projecting laterally from the body portion and being arranged in pairs, the two members of each pair being spaced apart. While the 65 leaves at either margin of the plate might be continuous from end to end, they are preferably made in two pairs, as shown, as being more easily bent to service position, and also for the purpose of reducing weight. 70 Preferably the plate is originally cast with its leaves parallel, and without curvature. The two members of each pair of leaves may be readily spread and properly curved by the introduction of a suitable wedge. The 75 leaves at one side of the plate may be properly spread before the assembling of the parts of the gear. The springs having been properly placed, with the retaining and spacing plate between them, its leaves at one 80 side having been spread, a suitable tool is inserted between the leaves at the opposite side, and by the blows of a hammer will cause the proper spreading, and thus securely lock the springs within the yoke.

85

I claim as my invention—

1. A spring-spacing and retaining plate comprising a body portion and a pair of leaves projecting laterally from each side edge of the body and having their adjacent 90 flat faces spaced apart.

2. A spring-spacing and retaining plate comprising a body portion and two pairs of leaves projecting laterally from each side edge of the body, the leaves of each pair having their adjacent flat faces spaced apart, the two pairs at each side of the body being 95 spaced apart laterally.

CHARLES J. NASH.
